UNITED STATES PATENT OFFICE.

DANFORTH H. ROYCE AND CYRUS TUFTS, OF COLUMBUS, OHIO, ASSIGNEES
TO JAMES G. PULLING, OF SAME PLACE.

STEAM-PUMP.

SPECIFICATION forming part of Letters Patent No. 445,412, dated January 27, 1891.

Application filed May 17, 1890. Serial No. 352,179. (No model.)

To all whom it may concern:

Be it known that we, DANFORTH H. ROYCE and CYRUS TUFTS, citizens of the United States, residing at Columbus, in the county 5 of Franklin and State of Ohio, have invented certain new and useful Improvements in Steam-Pumps; and we do declare the following to be a full, clear, and exact description of the invention, such as will enable others 10 skilled in the art to which it appertains to make and use the same.

Our invention has relation to improvements in steam-pumps; and it consists in the construction and novel arrangement of parts, as 15 hereinafter more fully described, illustrated in the accompanying drawings, and pointed out in the appended claim.

The objects of our invention are to provide a steam-pump of simple and inexpensive construction, that is perfectly noiseless when in 20 operation, and in which the use of auxiliary valves, tappets, and valve-rods are dispensed with; and in carrying out our invention we proceed as follows, reference being had to the 25 drawings for a better understanding of the details of construction and operation of the parts, and in which drawings—

Figure 1 is a vertical longitudinal section of a steam-pump embodying our improvements; Fig. 2, a transverse section on the line 30 $y-y$, Fig. 1; Fig. 3, a detail view of the screw-head of the cold-water-valve chest; Fig. 4, a sectional view on the line $x-x$ of Fig. 3.

Referring to the accompanying drawings, 35 in which like letters of reference indicate corresponding parts in all the figures, the letter A designates the frame of the pump, having secured thereto in any desired manner at one end the steam-cylinder B, carrying the steam-chest C, and at its opposite end the water-cylinder D and valve-chest E, all of the usual well-known construction.

As the particular construction of the steam-pumping engine is not claimed herein, but 40 will form the subject-matter of a separate application for patent, a detail description thereof is unnecessary in this application.

The letter F indicates the piston-rod pass-

ing through stuffing-boxes $g-g$, formed on the heads of the steam and water cylinders, and 50 carries at one end the piston-head and at its opposite end the water piston or sucker G, of any preferred construction.

H and H' indicate the induction and education ports in the water end of the pump, which 55 communicate with the valve-chest, as shown; and I indicates the valve located within said chest and is provided with a longitudinal recess i, in which fits one end of a set-screw i', passing through the side of the valve-chest, 60 and prevents said valve from revolving when the pump is in operation.

In order that water may be discharged against the ends of the valve I, thereby insuring its working, we provide the water-valve chest at each end with heads J, provided with ports j and firm auxiliary induction-ports j' communicating with said heads, as 65 shown in Fig. 1; and to prevent the slamming of the valve I against the heads J we place 70 at each end of the valve-chest rubber cushions K, and in order that said rubber cushions may be held in place against the action of the valve, a tight-fitting sleeve is placed 75 in the valve-chest abutting against the rubber cushions and provided with ports registering with the ports in the valve-chest.

The pump is provided with the usual steam, suction, and discharge pipes closed by suitable valves; and to readily permit of the pump 80 being drained when not in operation, pet-cocks L are placed in the bottom of the steam and water cylinders, as shown in Fig. 1. We do not desire to limit ourselves to the precise 85 construction herein shown and described, as many changes may be made without departing from the spirit of our invention.

The operation of our improved pump, taken in connection with the above description and accompanying drawings, will be readily understood by those skilled in the art.

Having thus described our invention, what we claim, and desire to secure by Letters Patent, is—

In a pumping-engine, the combination, with 95 the water-cylinder, of the water-valve chest

carried by said cylinder, provided at each end with a screw-threaded head ported on opposite sides, the rubber cushions within the water-valve chest held in position by a sleeve within the said chest, and the water-valve located within the said chest and adapted to be moved longitudinally by the action of the water against the heads thereof, as set forth.

In testimony whereof we affix our signatures in presence of two witnesses.

DANFORTH H. ROYCE.
CYRUS TUFTS.
